UNITED STATES PATENT OFFICE.

HENRY C. SWAN, OF OSHKOSH, WISCONSIN.

DESIGN FOR A SHANK FOR VEHICLE-STEPS.

SPECIFICATION forming part of Design No. 25,103, dated January 28, 1896.

Application filed December 21, 1895. Serial No. 572,932. Term of patent 14 years.

To all whom it may concern:

Be it known that I, HENRY C. SWAN, of Oshkosh, in the county of Winnebago and State of Wisconsin, have invented a new and original Design for Vehicle-Step Shanks, of which the following is a full, clear, and exact description.

In the accompanying drawing, the figure shows in perspective a shank for a vehicle-step embodying my design.

My design consists in a shank for a vehicle-step, shaped substantially as herein described and illustrated in the drawing, in which 2, 3 and 4 represent three arms which are secured to the vehicle, the arms 2 and 3 forming braces or auxiliary supports for the arm 4, which ex-

tends downwardly from their juncture and constitutes the shank proper.

I have indicated in dotted lines a step-pad as secured to the lower laterally-projecting end of the shank, but my design is independent of the particular form of step-pad employed, it consisting in the shank therefor.

I claim—

The design for a vehicle-step shank substantially as herein shown and described.

In testimony whereof I have hereunto set my hand.

HENRY C. SWAN.
